UNITED STATES PATENT OFFICE.

ROBERT J. ORR, OF WOODHAVEN, NEW YORK, ASSIGNOR OF ONE-HALF TO STEPHEN SCAMMACCA, OF BROOKLYN, NEW YORK.

WRITING MACHINE.

Application filed December 10, 1920. Serial No. 429,621.

To all whom it may concern:

Be it known that I, ROBERT J. ORR, a citizen of the United States, and a resident of Woodhaven, in the county of Queens and 5 State of New York, have invented certain new and useful Improvements in Writing Machines, of which the following is a specification.

This invention relates to writing machines, and particularly to machines for writing musical notations, the present invention being particularly adapted for use in connection with machines for writing music notation as disclosed in Patent No. 1,391,788 10 granted to me September 27, 1921, in which a writing sheet upon which the music characters and signs are to be impressed is carried by a platen to have to and fro longitudinal movement with a platen carriage with 15 the necessary mechanism to advance the carriage with the platen step by step letter space distances in the usual manner of typewriting machines, and in which means are provided to line space the platen at will 20 either forwardly or backwardly distances representative of one or more degrees, or multiples thereof, of a music staff.

It is the object of the invention to provide 25 indicating means to indicate the degree of advancing or retracting movement of the platen in line space direction and the writing position or printing point of a music character indicative of a music tone upon the writing sheet or paper carried by the 30 platen in relation to the music staff and the pitch of the tone of such music character.

It is a further object of the invention to 35 provide indicating means of this character arranged with representations of a plurality 40 of music staffs either one of which is adapted to co-operate with the platen to indicate the extent or degree of movement of the platen in line spacing direction and the writing or printing point of a music character 45 in predetermined position with relation to the music staff upon a writing sheet, the tone of such character and the pitch of the tone.

Other objects and advantages will herein- 50 after appear.

While the present invention relates par- 55 ticularly to a machine adapted for the writing of musical composition the invention is applicable to any of the well known com- mercial typewriting machines utilized for

the production of written speech by substituting for the characters representative of written speech impression making devices or characters representative of written music, and the embodiment of the invention 60 has been illustrated in connection with the platen carriage of the well known Underwood typewriting machine, only so much of the machine having been shown as is essential to an understanding of the invention. 65

In the drawings accompanying and forming a part of this specification, Figure 1 is a plan view of a platen rotatably mounted in a platen frame, only a portion of the ends being shown, with my improved indicating 70 means applied thereto, a writing scale being shown in front elevation in relation to the platen.

Figure 2 is an end elevation looking at the left of Figure 1. 75

Figure 3 is a cross sectional view of the platen and showing the relation of my improved paper shelf or table to the platen.

Figure 4 is an enlarged end elevation, partly in section, of a paper holding and 80 feeding finger utilized in connection with the paper shelf or table.

Figure 5 is a view of the paper finger looking at the top of Figure 4.

Figures 6, 7 and 8 are plan, front and end 85 elevations of a spring member to yieldingly hold the fingers shown in Figures 4 and 5 in adjusted position relative to the paper shelf or table.

Figure 9 is a front elevation, partly in 90 section, to show the mounting of the indicating means and the relation thereof to the platen.

Figure 10 is a plan view to show the relation of the paper shelf or table to the platen. 95

Figures 11 and 12 are sectional end views taken on the lines 11—11 and 12—12 of Figure 10, looking in the direction of the arrows.

Figures 13 and 14 are plan views showing 100 in a diagrammatical manner the arrangement of the representations of music staffs and symbols to denote music tones in relation to the staffs.

Figure 15 is an elevational view in section 105 of a pointer utilized in connection with the representations or indications of the music staffs, tones and pitch and the means to releasably retain the pointer in fixed position relative to such representations; and 110

Figure 16 is a plan view of a templet to be used in connection with the paper shelf or table for manually producing music signs in connection with mechanically written notation.

Similar characters of reference designate like parts throughout the different views of the drawings.

The embodiment of the invention is shown 10 in the drawings in connection with a cylindrical platen 17 fixed to an axle 17' whereby the platen is rotatably mounted in the ends 18 of a platen frame to have to and fro movement in line spacing direction by knobs 15 19 secured to the ends of the platen axle, type carried by type bars (not shown) being adapted to strike rearwardly against the front of the platen as is common in front strike writing machines. The invention is 20 adapted to be utilized in connection with finger key actuated means co-operating with toothed wheels or gears 20 at opposite ends of the platen, as set forth in my copending application hereinbefore referred to and to 25 which reference may be had, to line space the platen either forwardly or backwardly predetermined distances representative or equivalent of one or more degrees of diatonic signs above or below the initial note in the 30 writing of a music composition, and which may be a single degree, or a multiple of degrees, within a single octave or a multiple of octaves to enable the operator to collect and properly arrange the different parts of a 35 musical composition.

The paper or writing sheet, shown in a general way at P (Figure 3) to receive the impressions upon the platen is guided between feed rollers 21 and the platen and 40 around the platen by a table 22 extending between the ends of the platen, and the platen is releasably retained in pre-determined writing position by a yielding detent 23 co-operating with one or both of the toothed 45 wheels 20.

As stated it is an object of the present invention to provide means to facilitate the manual writing of music signs in connection with mechanically written characters of 50 music notation and for this purpose a paper shelf or table 24 is provided to extend along and above the platen, said shelf inclining downward and forward toward the platen with the leading edge of the shelf above the 55 line of writing on the platen. This shelf is preferably made of sheet material with the side edges bent up at right angles to provide guide ledges 25 for the side edges of the paper. The longitudinal edge of the shelf is 60 curled downwardly or curved, as at 26, to engage over studs 27 carried by brackets 28 secured to and projecting upwardly from the platen frame ends, said studs extending inwardly parallel with the platen. By so 65 mounting the shelf it is adapted to be ad-

justed to throw the leading edge thereof into or out of engagement with the platen. To maintain the writing sheet in contact and flat against the shelf as it is fed by the platen and feed rollers 21 rollers 29, shown as two 70 in number, are provided to engage with the top of the paper shelf. These rollers 29 are carried by resilient arms or fingers 30 mounted on a rod 31 extending longitudinally above the shelf and rotatably supported at 75 its ends in the shelf ledges 25. To maintain these fingers in position on the rod to yieldingly urge the rollers 29 against the paper shelf, the rod has a flattened portion 32 with which the free ends of both spring members 80 33 (Figures 6, 7 and 8) carried by the fingers is adapted to normally engage. By this arrangement the fingers may be rotated on the rod independently of each other to throw either one or both of the rollers into or out 85 of engagement with the paper shelf, and to adjust the fingers along the rod. The bow spring members are arranged with clips 34 adapted to engage in openings 35 (Figure 5) in the fingers 30 and may be bent over as 90 shown at 36 (Figure 4) to secure them to said fingers.

To throw both of the fingers simultaneously out of or into engagement with the paper shelf a finger lever 37 is secured to one 95 end of the rod outside of a shelf ledge 25, this finger lever being made of resilient material to operate as a detent to retain the rod and fingers in position with the rollers in or out of engagement with the paper shelf. For 100 this purpose the finger lever has a protuberance 38 extending laterally thereof toward the shelf ledge and when the rollers are in engagement with the paper shelf engages in a perforation in the shelf ledge, and when 105 the rod is adjusted to position with the fingers held in position with the rollers out of engagement with the paper shelf said protuberance engages with the top of the shelf ledge. To prevent throwing the 110 roller carrying fingers too far back an ear 39 is bent laterally from the shelf ledge to serve as a stop for the finger lever.

To reinforce the action of finger lever 37 a spring 67 may be provided on the rod 31 as 115 shown, or between the integral head of rod 31 and left ledge 25, as at 68. A collar 69 prevents the paper finger 30 at the right from slipping off from the portion of the rod 31 of larger diameter.

To facilitate the manual writing of music signs in conjunction with the mechanically written music notation on the writing sheet while engaging over the paper shelf there is provided a templet 40 of transparent sheet 125 material such as celluloid, (Figure 16). This templet is provided with an elongated curvilinear edge 70 of regular form to serve as a guiding edge for a pencil, pen or stylus in the writing of slurs and the like, and 130

at the left hand end with an irregular curved edge 71 to facilitate the writing of braces to connect staves. The templet also has portions stamped therefrom to provide interior 5 regular curved edges 72, 73 and an irregular curved edge 74. The templet is also arranged with a straight line 75 extending longitudinally and substantially centrally thereof whereby to parallel the templet 10 with the staff lines on the writing sheet to facilitate the marking or writing of angular lines. One of the longitudinal edges is provided with graduated sectional representation of spaces, bars and forms of music notation. In use the templet is placed over the paper on the paper shelf after the mechanically written music notation has been impressed thereon to mark on the sheet slurs and the like to tie or connect such music 15 notes as it is desired. By the arrangement of the fingers 30 carrying the rollers 29 the writing sheet is held flat and firmly against the table permitting of the templet to be used effectively as a tracing instrument in 20 conjunction with a pencil, pen or stylus.

In operation the writing sheet or paper is arranged with the regularly ruled and conventional music staff, and to accurately and correctly position notes, leger lines and 25 other music characters by name and degree within such staff and in the blank spaces above and below the same at will, means are provided to gauge or indicate the position of the regularly ruled music staff on the 30 writing sheet on the platen with relation to the printing point on the platen, the position of the music character or note indicative of a music tone upon such staff, or in position above or below the staff, and the 35 pitch of said tone. The embodiment of this indicating means illustrated in the drawings comprises a pair of heads or wheels 42, 43, mounted on a platen axle 17' at opposite ends of the platen outside of the ends of 40 the platen frame and within the platen rotating knobs 19. These heads as shown in Figure 9 are mounted upon the axle by sleeves 44 and are confined between collars 45 fixed to the sleeves and to reduced portions 46 of the platen knobs but of greater 45 diameter to support the same upon the sleeve 44 and knob portions 46, the portion of the bore of larger diameter co-operating with the knob portions of reduced diameter to 50 provide a recess for the engagement of an expansion spring 47 coiled about the sleeve and confined between the shoulder formed by the portion of the bore in the head of reduced diameter and a washer 48 abutting 55 against the reduced portion of the platen knob, the tension of the spring urging the wheel in a direction to frictionally engage the collar 45 whereby said heads will participate in the rotative movement of the 60 platen, and are adapted to have rotative ad-

justment relative to the platen for a purpose to be hereinafter described.

Each of the heads is arranged as a variable staff, tone and pitch indicator and for this purpose each head is provided with representations of a plurality of music staves circumferentially arranged around the periphery of the wheels with symbols of music tones in relation to the staves, the staves consisting of letters or the names of notes and 70 indicating the steps or degrees of the staves, and each lettered step or degree being numbered to indicate the degree of platen rotation necessary to position the platen to write or print a music character or note indicative 75 of a selected tone in proper relation to the music staff on the writing sheet. The indicator or gauge 42 is provided with the G or treble clef and the F or bass clef staves, as indicated diagrammatically in Figure 13, 80 and representative of $\frac{7}{3}$ octaves or the music arrangement of a pianoforte. The lettered or note named system of each staff is arranged with a system of numeral digits beginning with zero in the first lettered 85 space or note name of either staff, the initial note position in the G or treble clef staff being note F and in the F or bass clef staff A, and which is the initial music character printing position of the writing sheet on 90 the platen and in relation with which the writing sheet is aligned with the writing scale 49 positioned with relation to the writing line on the platen as shown in Figure 1, and which relative position of the platen to 95 the staff is indicated by a pointer 50 carried by an arm 51 to extend at a right angle therefrom, said arm being mounted loose upon the platen axle adjacent the platen frame end and retained in fixed position to the head 42. It will be obvious to 100 determine the positioning of the platen to position the music staff on the writing sheet to print a music character indicative of a tone with relation to said staff the degree 105 of rotation of the platen will be readily ascertained by the number adjacent the selected note name A, for example.

The music staves are arranged around the periphery of the head and to position the same in the range of vision of the operator the head is mounted upon the platen axle in the manner hereinbefore described to permit of rotative adjustment of the head relative to the platen, and the pointer is adjustable 115 relative to the positioning of the respective staves to facilitate the observing of the staves and the positioning of the platen. For this purpose the pointer carrying arm 51 has adjustment between a pair of stops 53 and is 120 releasably retained in position by a spring influenced detent 54 engaging in either one of a pair of recesses 52 in the platen frame end.

The representations of the G and F clef 130

staffs are arranged as multiple octave staffs, and to indicate the pitch of any selected tone or note name in either of the octaves of the staffs a pitch indicator is provided and is 5 arranged at the inner end of the head 42 having representations of the treble and bass clef staffs, as shown at 55 and 56 in Figure 11. The position of a selected tone or note name with relation to the pitch indicator is indicated by the pointer 50, the pointer being made of transparent material, such as celluloid, or of cut out and open frame metal structure, to permit of the ready 10 observation of the pitch indicator through 15 the same.

The head 43 is arranged in a manner similar to the arrangement of the staffs on the head 42 and just described except that said head has the representations of the tenor, 20 alto and soprano staffs, as indicated in a diagrammatic manner at 57, 58 and 59 in Figure 14. The position of the writing sheet on the platen relative to the printing point is indicated on the representations of the 25 music staffs by a pointer 50', similar in structure to the pointer 50, but said pointer is adjustable to three positions relative to the representations of the music staffs between a pair of stops 53', and releasably retained 30 in either of such positions by the detent engaging in either one of three recesses 60 in the platen frame end. The head having the representations of the tenor, alto and soprano staffs is provided with means to indicate 35 the pitch of any selected tone or note name in either of the tenor, alto or soprano staffs, and is arranged at the inner end of the head carrying said staff representations, as shown at 61, 62 and 63 in Figure 12, and 40 the position of a selected tone or note name with relation to said pitch indications is indicated by the pointer 50'.

The lettered or note name portion of the tenor, alto and soprano staffs are also arranged with the system of numbers beginning with zero in the first lettered space or note name of each of the staffs, such initial position in the soprano staff 59 being indicated by the note name D, in the alto staff 55 58 by the note name G, and in the tenor staff 57 by the note name E.

The treble or G staff and the soprano staff, are also provided with the numeral digit "8" with dots above the same, as shown at 64 55 and 65, and are written in relation to the three lined octave and are to indicate that the music characters being written are in an octave higher than the three lined octave. The bass or F staff is also provided with the 60 numeral digit "8" with dots below the same as shown at 66 and are written in relation to the contra octave and indicate that the music characters being written are in an octave lower than the contra octave.

In operation the writing sheet or paper 65 with the regular ruled and conventional music staff printed thereon is inserted between the feed rollers 21 and the platen and the first line of the treble staff on such sheet is aligned with the writing line scale 49, 70 with the pointer 50 adjusted to the position with the detent 54 engaging in the forward recess 52 in the platen frame end, as shown in Figure 10. The indicator or gauge wheel 42 is then adjusted relative to the platen to 75 bring the representation of the treble staff into the range of vision of the operator and set so that the note name F or one lined F and the numeral zero are in register with the pointer 50 when the indicator will be in position relative to the writing position of the sheet on the platen to begin writing of music characters in the treble staff. In the writing of music characters with the writing sheet adjusted to the writing position on the 80 platen and coinciding with the zero indication on the gauge or indicator the writing of higher notes are acts of addition and the writing of succeeding lower notes are acts of subtraction. However, 90 when writing notes below the zero indication writing, notes lower than zero are acts of addition and succeeding higher notes are acts of subtraction. These acts of addition and subtraction are mechanically effected 95 by rotating the platen by the knobs 19, or by the depression of platen advancing and retracting finger levers as set forth in my co-pending application hereinbefore referred to. With the writing sheet adjusted 100 on the platen and the writing position indicated on the variable staff, tone and pitch indicator by zero and one line F, to position the platen with the writing sheet to write the note E represented on the indicator by 105 two lined E in the fourth space of the staff, which is six degrees above zero, and indicates that the platen is to be retracted six degrees. To adjust the writing sheet to then 110 write the note three lined C which is located on the second leger line above the staff shown on the indicator as 11—C, and five degrees above the representation of the note 2 lined E or 6 E on the indicator in the fourth space of the music staff and in that case the platen must be retracted five degrees to position the 115 same to write the note three lined C, shown as 11—C on the indicator. Assuming that three lined C or 11—C has been written, to position the platen and writing sheet to 120 write the music character denoted by 7 F on the indicator, which is on the fifth line of the staff and four degrees below the note indication 11—C, this indicates that the platen must be advanced four degrees. To 125 write the music character indicated at 2 D or one lined D below zero on the initial position of writing on the writing sheet re-

quires the advancing of the platen two degrees. To then write the music character represented by small A or 5 A on the indicator which is on the second leger line below the staff and three degrees below 2 D, indicating that the platen must be advanced three degrees or steps to position the writing sheet in proper relation to the writing line to write such selected music character, and so 10 on. To combine notes above with notes below the zero position is an act of addition. Assuming the music character represented by one lined A or 2 A has been written which is above the zero position, and it is desired to 15 then write the music character indicated by one lined C or 3 C, it is necessary to add the increase of 2 A above zero and the decrease of 3 C below zero, which is 5 and indicates that the platen is to be advanced five degrees 20 to write the character 3 C.

After completion of the writing of the music characters of the treble staff to write music characters of the bass or F staff the platen is adjusted until the first line of the 25 bass staff on the writing sheet is in line with the writing line scale 49 when the pointer 50 is adjusted to engage the rear stop 53 with the detent 54 in engagement with the rear recess, and the indicator or 30 gauge 42 is adjusted rotatably relative to the platen to bring the representations of the bass staff into perspective and set so that the first space of the staff represented by zero A is in register with the pointer indicating the 35 initial writing position and from which position the writing of the music is proceeded with in a manner as set forth in connection with the G or treble staff.

When writing music, such as old music 40 and madrigals, in connection with the tenor, alto or soprano music staffs the indicator 43 with the representations of the variable staff, tone and pitch indications is utilized in a manner similar to that described in connection with the G or treble staff. The indicator 43 can also be used to write music notation in the C clef for violas, alto trombones, violincellos, tenor trombones, bassoons, etc.

50 To facilitate the writing of the music to readily ascertain the writing position of the music character from the variable staff, tone and pitch indicator, the staff and the places above and below the staff, as well as the 55 lines or graduations and symbols are arranged in contrasting colors on the indicator. All of the lines and symbols may be black, the field of staffs white, the field above the staffs orange and the field below the 60 staffs green, thereby enabling the eye to readily distinguish the nine tones of the regular staffs from the tones above and below the same on the indicator.

Variations may be resorted to within the

scope of the invention and portions of the 65 invention may be used without others.

Having thus described my invention I claim.

1. In a writing machine, the combination with a platen and means to move the same to and fro predetermined variable distances in line space direction, of a gauge to participate in the line spacing movement of the platen and arranged with indicia to indicate the writing position on the platen of a 75 music character indicative of a tone, its position relative to the music staff and the pitch thereof.

2. In a writing machine, the combination with a platen and means to line space the 80 platen to and fro predetermined variable distances, of a gauge participating in the line spacing movement of the platen and arranged with indicia, and a pointer to co-operate with the gauge to indicate on the 85 gauge the writing position on the platen of a music character indicative of a tone relative to the music staff and the pitch thereof.

3. In a writing machine, the combination with a platen and means to advance and retract the platen predetermined variable line space distances, of an indicator participating in the movement of the platen arranged with representations of a music staff, music tones in relation to said staff and the pitch 90 of the tones relative to the staff to indicate the writing position of a music character on the platen in predetermined relation to the staff and the pitch thereof.

4. In a writing machine, a rotatable platen, means to rotatively advance and retract the platen variable predetermined line space distances, a gauge participating in the movement of the platen arranged with representations of a music staff, music tones in 100 relation to said staff and the pitch of the tones, and a fixed pointer to co-operate with the gauge to indicate on the gauge the writing position on the platen of a music character in predetermined relation to the staff 105 and the pitch thereof.

5. In a writing machine, a platen, means to advance and retract the platen predetermined line space distances, and an indicator participating in the movement of the platen arranged with representations of a multiple octave music staff and indications of music tones in relation thereto with indications of the pitch of the tone relative to either of the octaves of the staff to indicate the writing 115 position on the platen of a music character in predetermined relation to either octave of the staff and the pitch of the tone.

6. In a writing machine, a rotatable platen, means to rotatively advance and retract the platen variable predetermined line space distances, and a gauge participating in the movement of the platen arranged with rep-

resentations of a plurality of multiple octave music staffs with symbols of music tones in relation to the respective staffs and the pitch of said tones in relation to the octaves to indicate the writing position on the platen of a music character with relation to either of the octaves of the respective staffs and the pitch of said tone.

7. In a writing machine, a rotatable platen; means to rotatively advance and retract the platen variable predetermined line space distances, a gauge participating in the movement of the platen arranged with representations of a plurality of multiple octave music staffs with symbols of music tones in relation to the staffs and the pitch of said tones in relation to the octaves, and a pointer to co-operate with either of said music staffs to indicate the writing position on the platen of a music character with relation to either of the octaves of the respective staffs and the pitch of said tone, said pointer being adjustable relative to the music staffs of the gauge for the purpose specified.

25 8. In a writing machine, a platen; means to advance and retract the platen variable line space distances; and a pair of indicators participating in the movement of the platen, each indicator arranged with the representations of a music staff and symbols of music tones in relation to the respective staffs and the pitch of said tones for the purpose specified.

9. In a writing machine, a platen; means 35 to advance and retract the platen variable line space distances; and a pair of indicators participating in the movement of the platen, each indicator being arranged with representations of multiple octave music staffs with symbols of music tones in relation to the octaves of the staffs and the pitch of said tones in relation to the octaves to indicate on the platen the writing position of the music character indicative of a predetermined tone on either octave of a staff 45 and the pitch of the tone.

10. In a writing machine, a platen rotatable to and fro predetermined distances in line space direction, a circular head rotatable 50 with the platen having representations of a music staff circumferentially arranged around the periphery gauged to coincide with the line space movement of the platen, and symbols of music tones in relation to the staff.

55 11. In a writing machine, a platen rotatable to and fro predetermined distances in line space direction, a circular head rotatable with the platen having representations

of a music staff circumferentially arranged 60 around the periphery gauged to coincide with the line space movement of the platen, and symbols of music tones in relation to the staff, and pitch indications circularly arranged at the end of the head in relation to 65 the music staff.

12. In a writing machine, a platen rotatable to and fro predetermined distances in line space direction, a circular head rotatable with the platen having representations of 70 a music staff circumferentially arranged around the periphery gauged to coincide with the line space movement of the platen and symbols of music tones in relation to the staff, and pitch indications circularly 75 arranged at the end of the head in relation to the music staff, and a pointer to co-operate with the representations of the music staff, tones and pitch on the head to indicate the writing position on the platen of a 80 music character with relation to the staff and the pitch thereof.

13. In a writing machine, a platen rotatable to and fro predetermined distances in line space direction, a circular head rotatable 85 with the platen having representations of a plurality of music staffs circumferentially arranged around the periphery with symbols of music tones in relation thereto, and pitch indications of said tones relative to the respective staffs circularly arranged at the end of the head, and a pointer to co-operate with the representations of the staffs, tones and pitch on said head to indicate the writing position on the platen of a predetermined 90 music character with relation to either of the staffs and the pitch thereof, said pointer having adjustment relative to the music staffs for the purpose specified.

14. In a writing machine, a platen rotatable to and fro predetermined line space distances, a pair of heads located at opposite ends of the platen and adapted to participate in the rotative movement of the platen, each of said heads being arranged with 100 representations of a music staff with symbols of music tones in relation to the staff and the pitch of said tones, and a pointer to co-operate with the representations on the heads to indicate the writing position on 105 the platen of a predetermined music character relative to the staff and the pitch thereof.

Signed at New York city, in the county of New York and State of New York, this 115 7th day of December 1920.

ROBERT J. ORR.
